UNITED STATES PATENT OFFICE.

JAMES E. WEAVER, OF TEMPERANCEVILLE, PENNSYLVANIA.

IMPROVEMENT IN OIL-CANS AND OILERS.

Specification forming part of Letters Patent No. 58,157, dated September 18, 1866.

To all whom it may concern:

Be it known that I, JAMES E. WEAVER, of Temperanceville, in the county of Allegheny and State of Pennsylvania, have invented a new and useful Improvement in Oil-Cans; and I do hereby declare that the following is a full and exact description thereof, reference being had to the accompanying drawing, and to the letters of reference marked thereon.

The nature of my invention consists in furnishing an oil-can with an air-chamber by dividing the body of the can into two parts, and connecting an air-tube with one of the parts, the whole being constructed, arranged, and operating in the manner hereinafter described.

To enable others skilled in the art to make and use my invention, I will proceed to describe its construction and operation.

In the accompanying drawing, which represents a longitudinal section of my improved oil-can, *a* represents the body of the can. *b b'* represents the conductor, which is screwed to the body *a* by a screw on the end of the conductor and a female screw in the mouth of the can, the arrangement of which is clearly shown at the point marked *e*. The body of the can is divided into two parts by the division-piece marked *d*.

c represents a tube, which is connected to the body of the can, and communicates with air-chamber *R*. To this tube *c* I connect a hollow wooden rod, furnished with a mouth-piece, so that I can blow air into the air-chamber *R*, when I desire to oil journals not within reach of the operator.

The tube *b b'* is made in two sections, so as to form a straight or curved conductor, as may be desired.

f represents the ordinary handle of the can.

Oil is forced out at or through the conductor *b b'* by forcing air through tube *c* into chamber *R*. This is only done when oiling journals not within the ordinary reach of the operator. Oil is put in the can in the usual manner.

What I claim is—

The arrangement of the division *d* and tube *c*, when used in connection with the body *a* and conductor *b b'*, as herein described and set forth.

JAMES E. WEAVER.

Witnesses:

JAMES J. JOHNSTON,
A. C. JOHNSTON.
